UNITED STATES PATENT OFFICE.

OTTO ARNDT KUNERT AND THEODOR FREIHERR KORB VON WEIDENHEIM, OF VIENNA,
AUSTRIA-HUNGARY.

RAILWAY-SPlice WITH FISH-PLATES.

1,079,866.

Specification of Letters Patent. Patented Nov. 25, 1913.

Application filed March 28, 1912. Serial No. 686,855.

To all whom it may concern:

Be it known that we, OTTO ARNDT KUNERT, subject of the King of Hungary, and THEODOR FREIHERR KORB VON WEIDENHEIM, subject of the Emperor of Austria, residing at Steingasse 36, Vienna, III, in the Province of Lower Austria and Empire of Austria-Hungary, have invented certain new and useful Improvements in Railway-Splices with Fish-Plates, of which the following is a specification.

Our present invention relates to improvements in railway splices with bridging fish-plates, which are secured to the rail ends and has for its object to take up the wheels at the rail joint and to guide them from one rail to the other. By means of the said bridging fish-plates the shocks against the wheels running over the rail joint are diminished. But with the arrangements hitherto used such shocks in case the wheels drive from the rail upon the fish plate and run down from the same upon the rails, could not be avoided, for the reason that with the fish-plates commonly used a sudden lifting or lowering of the wheels takes place, the running or head face of such wheels becoming worn away during working at a part of its breadth, so that owing to the stepped or shouldered tread of the wheel the latter cannot drive up and down without shock. This drawback is obviated by the present invention. According to this invention the head or upper surface of the bridging fish-plate is beveled off at the outer side by a sloping transverse face, which inclines toward both ends of the fish-plate, so that the beveled or sloping part of the top surface or head of the fish-plate increases in breadth toward both ends, while the inner side of the fish-plate head, *i. e.*, the side adjacent to the rails, is even or inclines slightly toward both ends of the fish-plate, at a part increasing in breadth toward the middle. The said construction has for its object that the wheels, however great the wear may be, always find points of the sloping face from which they may drive up and run down the fish-plate gradually so as to avoid any shock which may be exerted upon the wheel otherwise.

The arrangement may of course be such that the fish-plate will be wedged automatically within the groove of the bottom plate or between the said bottom plate and the rail,

in case the fish plate will be moved lengthwise owing to the migration tendency of the rails, so that migration of the rails is avoided perfectly. Moreover the invention enables especially the lower parts of the joint to be attached closely and tightly together, and this circumstance may be made use of preferably in electric railway plants for direct current transmission. In the said plants the fish-plates hitherto used are not sufficient at present for direct current transmission in case the rail is used as current conductor. Therefore copper rail bonds are used for conductively connecting the rails, but such connecting bonds are expensive and give rise to other inconveniences, as *e. g.*, liabilities to injury from atmospheric influence or vandalism. The lower adjacent faces of the fish plate and rail being tightly jointed together according to the present invention, separate connecting pieces such as copper bonds are dispensed with, for by the tight and close connection of the separate parts a sufficiently reliable current transmitting face is formed. In order to increase the security in the electric connection and to prevent loss of the transmitting capacity by formation of rust the fish-plates may be provided at the inner side with a galvanic conducting coating.

With the railway splices hitherto used such coating would be useless, for the reason that the several parts contact with each other only in few points and would therefore be scoured off constantly by the shocks, so that the coating would disappear. In the construction according to the present invention such danger is obviated owing to the extended contacting faces and the tight, intimate contact of the same. Instead of a coating a conducting mass such as mercury amalgam may be used.

The railway splice according to the present invention responds therefore to all requirements in respect to avoiding shocks, security of the connection and reliable current transmitting.

The accompanying drawings show an example of execution of the present invention.

Figure 1 shows the improved rail joint in cross section, Fig. 2 in elevation and Fig. 3 in plan view, and Fig. 4 shows a plan view of the fish-plate, a series of consecutive cross sections being represented below. Fig. 5 shows the fish-plate in a perspective view

and Fig. 6 is a horizontal section taken on the line A—A in Fig. 1.

The rail *a* with the lower flange *m* is held on both sides by two fish-plates *b* and *c* which fit partly to the rail head, the lower parts of *b* and *c* being closely adapted or connected to the web and lower flange of the rail *a*. The head or running face of the fish-plate *c* (Fig. 4) is at the inner side *i. e.*, at *l*, even or inclines slightly toward both ends of the fish-plate, while it is beveled at the outer side by a sloping transverse face which inclines toward both ends of the fish-plate. The sloping part of the upper or running face of the fish-plate increases therefore in breadth toward both ends. As shown in Fig. 4 the sloping face may also be composed of continuous surfaces with successive cross-sections *k*, *i*, *k* of different inclinations. The parts *k*, *i*, *k* may have also equal inclination or equal sloping angles in transverse direction and different inclination in longitudinal direction. But the inclination in transverse direction (transverse slope) may be greater at the ends (angle of inclination α) and smallest in the middle of the fish-plate (angle of inclination β). By this means the intended gradual running up and down of the wheel *h* is realized. In this way a carrying surface will be obtained which is adapted to all shapes of wheel rim, for it results from the dotted line (Fig. 1) which represents the profile of a strongly worn wheel rim, that the wheel will always be lifted, and lowered gradually however great the wear of the wheel tread in breadth and height may be.

With the usual fish-plates, the upper or running surface of which has no inclination in transverse direction, but is beveled at the ends in longitudinal direction, the wheel will be lifted on running over the rail joint or fish-plate by such degree as corresponds to the depth of the recess resulting from the wear of the wheel tread. Therefore shocks are exerted to the wheels running up and down the fish-plate. Such shocks are perfectly avoided by the shape according to the present invention, for the reason that sudden lifting and lowering of the wheels cannot take place. At points of track curvatures, where the carriages will be thrown outwardly, it may happen that the unworn edge part of the tread of the inner wheels wholly travels upon the elevated part of the fish-plate. But, as the wheel runs up in a gradually mounting way, in as much as the unworn or elevated edge part finds always a suitable point of the sloping face at the end of the fish-plate, from which point the said edge part may begin to run up, violent shocks or thrusts are avoided under all circumstances. The same is the case also for every position of the wheel on the track, no matter how the wheel travels

by a greater measure upon the outer or inner side of its rail. The said particular and perfect effect results only from the special construction of the bridging fish-plate as can be understood by the sections illustrated in Fig. 4 and by the perspective view (Fig. 5).

The two fish-plates *b* and *c* are rigidly connected to the rail *a* by the bolts *g*. The lower flanges or bases of the two rails are supported by a base plate *d*, which is provided at both sides with upper longitudinal projections *e*. The projections *e* are provided at their inner sides with longitudinal grooves *p*, which are closed at both ends by oblique or curved faces *p'*. Correspondingly the ends of the lower flanges *f* of the fish-plates engaging the grooves are tapered or curved conically as at *f'*, so that, in case the rail has a tendency to creep, the tapered or conical end of the fish-plate will be wedged at *p'* and prevent such migration. If violent transverse thrusts take place the lower flange *f* of the fish-plate will be forced into the respective groove *p*, owing to the action of the lower part of the fish-plate which part acts as a bell crank lever, so that the rail will be given greater rigidity in lateral or transverse direction.

The spaces between the flanges *f* and the lower flange or base *m* of the rail *i. e.* the grooves *p* of the base plate *d* may be filled up with a current conducting mass such as mercury amalgam, or thin sheets *o* of copper or the like may be interposed for the purpose of using the rails as current conductors without special rail bonds at the joints.

It will be observed that the two fish-plates *b* and *c* will be applied and removed only by tilting the same inwardly and outwardly in lateral direction, for the reason that the groove *p* is closed at both ends by a tapered or curved face *f'*, whereas the known fish-plates are to be moved lengthwise into or out of the groove of the base plate, such groove being open at both ends.

Claims—

1. In a railway splice, the combination of a fish-plate, a base plate supporting the ends of the joined rails and being provided with a recess closed at both ends by oblique or tapered surfaces, the opening of the said trough shaped recess being directed toward the rails, a lower flange of the fish-plate engaging said recess and being tapered at both ends so as to fit said oblique or tapered surfaces at the ends of the said recess.

2. In a railway splice, the combination of fish-plates on both sides of the rail joint, a base plate supporting the ends of the joined rails and being provided at each side with a recess closed at both ends by oblique or tapered surfaces, the opening of said trough shaped recess being directed toward the rails, a lower flange of the respective fish-

plate engaging said recess and being tapered at both ends, the head of the outer fish-plate being provided with means to carry the wheel from one rail over the joint to the other rail without shocks.

3. In a railway splice, the combination of fish-plates on both sides of the rail joint, a base plate supporting the ends of the joined rails and being provided at each side with a recess closed at both ends by oblique or tapered surfaces, the opening of said trough shaped recess being directed toward the rails, a lower flange of the respective fish-plate engaging said recess and being tapered at both ends, the surface of the head of the outer fish-plate being composed of an inner longitudinal part increasing in breadth toward the middle of the fish-plate and of an outer longitudinal part which is beveled off by a transversely sloping face and increased in breadth toward both ends of the fish-plate, said beveled part extending from one end of the fish-plate to the other.
4. In a railway splice, the combination of fish-plates on both sides of the rail joint, a lower flange on each fish-plate curved at its ends, a base plate supporting the ends of the rails and provided with recesses closed and

tapering at the ends, the openings of said trough shaped recesses being directed toward the rails, said flanges engaging the respective recesses of the base plate so as to fit wholly therein.

5. In a railway splice, the combination of fish-plates on both sides of the rail joint, a lower flange of each of said fish-plates provided with curved ends, a base plate supporting the ends of the rails and provided with recesses, which are closed and tapering at the ends and are engaged by the respective lower flanges of the fish-plates which flanges are provided with tapered ends, the said fish-plates fitting snugly to the faces of the web and base of the rails and constituting in transverse direction a bell crank lever, the lower arm of which is wedged fast in the respective recess of the base plate, in case the upper arm of the said bell crank lever is screwed fast.

In testimony whereof we affix our signatures in presence of two witnesses.
